HOLDER FOR DENTAL SUPPLIES OR THE LIKE

Samuel R. Kleiman, 5214 Northwestern Ave., Chicago, Ill.

Filed Jan. 23, 1961, Ser. No. 63,640

Term of patent 14 years

(Cl. D4—3)

FIG. 1 is a perspective view of a holder for dental supplies or the like showing my new design;

FIG. 2 is a front elevational view thereof; and

FIG. 3 is a side elevational view thereof.

The side not shown is substantially the same as that shown in FIG. 3 and the back is conventionally plain.

I claim:

The ornamental design for a holder for dental supplies, or the like, substantially as shown and described.
